No. 11,093

March 25, 1879

UNITED STATES PATENT OFFICE.

ROYAL E. WHITMAN, OF NEW YORK, N. Y.

DESIGN FOR RIDING-SADDLES.

Specification forming part of Design No. **11,093**, dated March 25, 1879; application filed February 26, 1879.
[Term of patent 14 years.]

To all whom it may concern:

Be it known that I, ROYAL E. WHITMAN, of New York city, State of New York, have invented a Design for Riding-Saddles, of which the following is a specification:

The nature of my design is fully represented in the accompanying photographic illustration, to which reference is made.

Figure I is a side view, and Fig. II a plan view.

C is the seat. B is the horn; D, the cantle; E, the front, and F the rear, bearing.

The line C, as shown in Fig. I, descends in a gradual curve from the point *c* to its lowest point at or near the center of the seat, and from thence rises in a gradual curve to the highest point of the cantle D. The cantle D, being thus partially defined in side profile by the line of the seat C, is completed by its rear lines *d g*, which unite, as shown in Fig. I, at the point *h*. From the front base of the horn B, at a point marked *x*, the line *m* inclines outward for some distance in nearly a straight line before being rounded to extend inwardly to unite with the line *v* in outlining the front, bottom, and rear of the saddle. The front E is of the general form of the English saddle-tree known as the "cut-back." From the points *c x* the horn B rises from the pommel, as seen in Fig. I, in the general form of a column, surmounted by the nearly flat head *b*.

Fig. II shows in the plan view of the saddle the elongated slot *s*, extending from the horn B, with its head *b* nearly circular in plan view to the cantle.

I am aware that all of the lines and configurations shown in this saddle are not new of themselves, and have been employed in part in other saddles, and notably in the one for which patent was granted me September 24, 1878, No. 10,844.

The distinctive character of my design is found in the combination, with the slot *s*, front E, rear bearing F, and cantle D, of the horn B, by which a saddle is formed having an appearance entirely different from any before made.

In the photographic illustrations the saddle-tree is shown; but as in covering it with skin or leather the form is no more changed than it would be by a coat of paint, the picture is to all intents and purposes a faithful representation of the configuration claimed by me as a new design for saddles.

What I claim as my invention is—

The design for riding-saddles, substantially as shown and described.

R. E. WHITMAN.
